ELECTROMAGNETIC UNIT FOR ACOUSTIC INSTRUMENTS

Application filed February 27, 1931, Serial No. 518,804, and in Germany February 15, 1930.

This invention relates to acoustic instruments and particularly to sound reproducers such as loud speaking telephones and has special reference to driving units for loud speakers employing large diaphragms.

Loud speakers generally do not reproduce the original sounds as faithfully as is desirable; considerable losses occurring particularly for example, in the reproduction of sounds of low frequency. The object of the invention is to provide a driving unit which will reproduce as uniformly as possible the various frequencies of the original sounds, while particularly avoiding losses of the lower frequencies.

According to the present invention an electromagnetic unit for acoustic instruments such as sound reproducers has outer and inner magnetic poles on both sides of the axis of vibration of a vibratory armature, the arrangement being such that the outer poles exert on the armature a turning moment which is in opposition to that exerted by the inner poles with the result that the amplitude of vibration of the armature is proportional to the difference between the opposing moments.

Further according to the invention an electromagnetic unit for acoustic instruments employing a vibratory armature has at least four polar faces of common polarity disposed opposite an equal number of polar faces of opposite polarity and field magnets of substantially equal intensity of magnetization arranged in such a manner that substantially equal magnetic flux is produced in the halves of a pole shoe which bridges like poles of the field magnets.

Preferably according to the invention the vibratory armature of the electromagnetic unit is provided with lateral extensions designed to retain the vibratory armature in the normal position. In accordance with a further feature of the invention in an electromagnetic driving unit for acoustic instruments employing a vibratory armature the position of the pole shoes relatively to one another is determined by the positions of screws provided to secure them to the field magnets.

In order that the invention may be more clearly understood and readily carried into effect, a driving unit will now be described by way of example and in connection with the accompanying drawings in which

55

Figure 1 is a front elevation,

Figure 2 is an end view,

Figure 3 is a side view and

Figure 4 is a sectional end view taken on the line IV IV of Figure 1.

60

Figure 5 is a plan view of the vibratory armature.

65

Two permanent horseshoe magnets 1, 2 of equal intensity of magnetization provide a magnetic field and are arranged in spaced relation one above the other with like poles adjacent. Laminated pole shoes 3 and 4 bridge like poles of the permanent magnets so that equal flux density obtains in each half of the pole shoes.

70

The laminated pole shoes 3 and 4 are secured to the magnets by screws 3_a, 4_a so that the correct spacing between the pole shoes is obtained by placing the holes for the screws in appropriate positions in the magnets. The laminations have portions stamped out of them in order to form pole pieces N₁, N₂, N₃, N₄, S₁, S₂, S₃, and S₄. In the outer recesses thus formed are coils 5 and 6 which carry the currents to be reproduced while the central recesses form air gaps between the poles N₂ and N₃, and S₂ and S₃. The input leads to the device are attached to terminals on a strip 7.

75

Screwed to angle brackets 8 is a vibratory armature 9 formed with lateral T shaped extensions 10, 11. The neck portions 10, 11 are of such elasticity that while they permit free vibration of the armature about the axis 12, the armature is normally retained in a central position in the air gap between the pole pieces N₁, N₂, N₃, N₄ oppositely disposed respectively to pole pieces S₁, S₂, S₃, S₄. To one end of the armature is attached a rod 13 secured to an adjustable springy strip 14 which carries a pin 15. A conical sound radiating diaphragm, not shown, is actuated by the pin 15 to which it is attached.

80

Before describing the operation of the driving unit it is desirable to state that when

100

in the normal position the vibratory armature is in a mechanically and magnetically balanced condition. There is no mechanical stress on the armature due to magnetic forces 5 when there is no current flowing in the coils 5 and 6 and as the flux variation in operation is confined to the pole shoes, the field of the permanent magnets is not detrimentally affected and remains constant. The general 10 efficiency of the driving unit is thus increased.

In operation the varying currents are applied to the terminals of the device so that their direction of flow causes the production 15 of magnetic poles n_1 s_1 n_2 s_2 in the armature 9 as indicated in Figure 4 of the drawings. The pole n_1 will be repelled by the pole N_1 and will be attracted to pole S_1 , while s_1 will be attracted to N_2 and repelled by S_2 .

The pole n_2 will be repelled by N_3 and attracted to S_3 , while the pole s_2 will be repelled by S_4 and attracted to N_4 . The outer poles N_1 N_4 and S_1 S_4 exert a greater turning moment on the armature 9 about its axis 12 than the opposing turning moment exerted by 25 the inner poles N_2 N_3 and S_2 S_3 . The effective movement of the armature about its axis is of course the difference between the opposing turning moments.

It is found that a more uniform output 30 and less distortion of the lower frequencies is obtained with a driving unit constructed in accordance with the present invention. The opposing turning moment exerted by the inner poles on the armature serves to damp the 35 vibrations at the ends of the armature resulting in a uniform reproduction of low frequency sounds.

I claim:

1. An electromagnetic driving unit for 40 acoustic instruments comprising a field magnet, a vibratory armature, an input winding for magnetizing said armature and outer and inner polar extensions of said field magnet located on both sides of the axis of vibration of said armature, said outer polar extensions exerting on said armature a turning moment which opposes the turning moment exerted on said armature due to the inner polar extensions such that the resultant amplitude of vibration of said armature is proportional to the difference between the said opposing moments.

2. An electromagnetic driving unit for 45 acoustic instruments comprising a field magnet, a vibratory armature, an input winding for magnetizing said armature and outer and inner polar extensions of said field magnet of like polarity on each side of the axis of vibration of said armature, said outer and inner polar extensions being disposed opposite co-operating polar extensions of opposite polarity.

3. An electromagnetic driving unit for 50 acoustic instruments comprising a field magnet, a vibratory armature, an input winding

for magnetizing said armature, outer and inner polar extensions of said field magnet on both sides of the axis of vibration of said armature, said outer polar extensions exerting on said armature a turning moment which opposes the turning moment exerted on said armature due to said inner polar extensions and said vibratory armature having lateral extensions tending to retain it in the normal position.

4. An electromagnetic driving unit for 55 acoustic instruments comprising a field magnet, a system of pole pieces for distributing the field from said field magnet, a vibratory armature and an input winding for magnetizing said armature said system of pole pieces being readily detachable from said field magnet and comprising outer and inner polar extensions on both sides of the axis of vibration of said armature, said outer polar extensions exerting on said armature a turning moment which opposes the turning moment exerted on said armature due to said inner polar extensions.

5. An electro-magnetic driving unit for 60 acoustic instruments comprising a field magnet, a vibratory armature, an input winding for magnetizing said armature, and outer and inner polar extensions of said field magnet located on each side of the axis of vibration of said armature, all said extensions having like poles opposite each face of the armature, said armature when energized by said winding being subjected to opposing turning moments from said outer and inner polar extensions respectively.

6. An electro-magnetic driving unit for 65 acoustic instruments comprising a field magnet, pole pieces connected to the poles of said magnets and provided with at least four polar extensions of like polarity and substantially equal magnetic intensity, a vibratory armature interposed between said pole pieces and pivoted to vibrate about an axis midway of its length, two of said polar extensions being farther from said axis than another two, and a divided input winding for magnetizing said armature in such a manner that the amplitude of vibration of the armature is proportional to the difference between the turning moments thereby created between said armature and the outer and inner polar extension.

7. An electro-magnetic driving unit for 70 acoustic instruments comprising a plurality of field magnets, a pair of pole pieces each bridging like poles of said magnets and each shaped with four polar extensions of substantially equal magnetic intensity, a centrally pivoted vibratory armature disposed between said pole pieces, and an input winding for magnetizing said armature.

8. An electro-magnetic driving unit for 75 acoustic instruments comprising a field magnet, a system of pole pieces including four

pairs of polar extensions for distributing the field from said magnet, a vibratory armature and an input winding for magnetizing said armature, said armature having resilient lateral extensions secured at their ends to said magnet for retaining said armature in the normal central position.

9. An electro-magnetic driving unit for acoustic instruments comprising a field magnet, a system of pole pieces including at least four pairs of polar extensions for distributing the field from said magnet, a vibratory armature, an input winding mechanically supported on said pole pieces for magnetizing said armature, said armature having resilient lateral extensions and means for securing said extensions to said pole piece system so that said pole pieces, said armature and said input winding constitute a unit which is readily detachable from said field magnet.

10. An electro-magnetic driving unit for acoustic instruments comprising a field magnet, a centrally pivoted vibratory armature, a system including pole pieces having at least four pairs of polar extensions, two of said pairs being located at each side of the armature pivot and at different distances therefrom, one polar extension of each pair being located at one face of the armature and the other polar extension of each pair being located at the other face of the armature, all said polar extensions at each face of the armature being of like polarity for distributing the field from said field magnet, and an input winding for magnetizing said armature, said winding being divided to form two coils located one on each side of the axis of vibration of said armature.

40 In witness whereof I hereunto subscribe my name this 10th day of February 1931.

WILHELM HASSEL.
